UNITED STATES PATENT OFFICE.

FREDERICK CARLYLE RILE, OF CHICAGO, ILLINOIS.

DESIGN FOR A CUFF BUTTON OR SIMILAR ARTICLE.

Application filed March 2, 1928. Serial No. 25,650. Term of patent 14 years.

To all whom it may concern:

Be it known that I, FREDERICK CARLYLE RILE, a citizen of the United States, residing at Chicago, in the county of Cook and State of Illinois, have invented a new, original, and ornamental Design for a Cuff Button or Similar Article, of which the following is a specification, reference being had to the accompanying drawing, forming part thereof.

I claim:

The ornamental design for a cuff button or similar article, as shown.

FREDERICK CARLYLE RILE.
